Primary Examiner — Kevin Rudzinski*(74) Attorney, Agent, or Firm* — Shook Hardy Bacon L.L.P.**CLAIM**

The ornamental design for a tiki torch holder, as shown and described.

DESCRIPTION

FIG. 1 is a perspective view of a tiki torch holder of the present invention;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof; and,

FIG. 7 is a bottom plan view thereof.

The evenly spaced broken lines shown in the drawings are directed toward environment, are for informational purposes only, and form no part of the claimed design.

The surface shading lines on the claimed portion are provided only to indicate the character and/or any contour or curvature of the surfaces. They do not indicate color, texture, markings that actually exist thereon, indicia, graphic representations, surface treatment, or any other ornamentation applied to the article.
